Primary Examiner — Aula Soroush*(74) Attorney, Agent, or Firm* — Winston Hsu(57) **CLAIM**

The ornamental design for a cat kennel, as shown and described.

DESCRIPTION

FIG. 1 is a top, front, and right side perspective view for a cat kennel showing my new design;
 FIG. 2 is a top, rear, and left side perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof;
 FIG. 8 is a bottom plan view thereof;
 FIG. 9 is a top plan view thereof in an unassembled configuration; and,
 FIG. 10 is a front elevation view of the cat kennel showing in an environment in which it may be used.
 The broken lines depict portions of the cat kennel and environment that form no part of the claimed design.
